Keyes Fibre Company, Portland, Maine, a cor-
poration of Maine

Application June 12, 1941, Serial No. 101,423

Term of patent 14 years

To all whom it may concern:

Be it known that I, Lawrence J. King, a citizen
of the United States, residing at Fairfield, in the
county of Somerset, State of Maine, have in-
vented a new, original, and ornamental Design
for Fibrous Plate, of which the following is a
specification, reference being had to the accom-
panying drawing, forming part thereof.

Fig. 1 is a perspective view of a fibrous plate
showing my new design.

Fig. 2 is a sectional view on the line 2—2, of
Fig. 1.

I claim:

The ornamental design for a fibrous plate, as
shown.

LAWRENCE J. KING.
